(57) **CLAIM**

The ornamental design for a razor cartridge dispenser tab, as shown and described.

DESCRIPTION

FIG. 1 is a top right perspective view of a razor cartridge dispenser tab showing my new design;

FIG. 2 is a top plan view thereof;

FIG. 3 is a rear elevational view thereof;

FIG. 4 is a right side view thereof; the left side view being a mirror image thereof;

FIG. 5 is a front elevational view thereof; and,

FIG. 6 is a bottom plan view thereof.

The broken lines shown in all the views is for illustrative purposes only and forms no part of the claimed design.
